JAMES HORTEN & JOHN MARTINO, OF PHILADELPHIA, PA.,
ASSIGNORS TO D. STUART AND R. PETERSON, OF SAME PLACE.

Letters Patent for a Design, No. 26, dated March 19, 1861.

SPECIFICATION.

TO ALL WHOM IT MAY CONCERN:

Be it known, that we, JAMES HORTON and JOHN MARTINO, of Philadelphia, Pennsylvania, have invented or produced a new and original Design for Plates of a Cooking Stove; and we do hereby declare that the accompanying drawing and the following explanation of the same form a full, clear, and exact description of the said design.

Fig. 1 of the drawing is a face view of the front plate of the stove.

Fig. 2, one of the side plates.

Fig. 3, the back plate.

Fig. 4, a view of the upper edge of the front plate; and fig. 5, a vertical section in outline of the front plate on the line 1 2, fig. 1.

The exterior shape of the front plate will be best observed on reference to figs. 4 and 5, there being a projection *a* at the upper edge of the form represented by these figures.

This front plate has two doors, each being edged with a denticulated moulding, and each having a foliated ornament, and near the opposite vertical edges of the plate are the foliated ornaments represented in the drawing. The side plate, fig. 2, has a large oven door and a smaller door, above which is a panel, both of the doors as well as the panel being edged with a moulding, and having foliated ornaments similar to the mouldings and ornaments on the doors of the front plate.

The back plate, fig. 3, is also ornamented, as clearly shown in the drawing.

We claim the combination and arrangement of the ornamental figures and

Horton and Martino's Design for a Stove.

---

forms represented in and by the accompanying drawing, forming together an ornamental design for the front side and back plates of a cooking stove.

In testimony whereof, we have signed our names to this specification, in the presence of two subscribing witnesses.

JAMES HORTON,
JOHN MARTINO.
